(57) CLAIM

The ornamental design for a novelty clip for attachment to shoelace, as shown and described.

DESCRIPTION

FIG. 1 is a front, right perspective view of a novelty clip for attachment to shoelace showing our new design;

FIG. 2 is a bottom view thereof;

FIG. 3 is a top view thereof;

FIG. 4 is a left side view thereof;

FIG. 5 is a right side view thereof;

FIG. 6 is a front view thereof; and,

FIG. 7 is a back view thereof.

The dashed lines in FIGS. 1 and 6 show where a word or message or image may be placed on the clip and do not form a part of the claimed design.

1 Claim, 4 Drawing Sheets
